UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR CASING OF SODA-WATER APPARATUS.

Specification forming part of Design No. 7,063, dated December 16, 1873; application filed November 20, 1873.
[Term of Patent 14 years.]

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

In the photograph, A represents the body or main portion of the casing of a soda-water apparatus, which, from *a* to *b*, is square in cross-section. The upper portion or top C is composed of four inclined surfaces of diamond shape, which slope or incline inward and upward from each corner, at *c*, to a peak or apex, *d*, which may be made flat to receive a statue

or other ornament. On each of the four sides of the casing is a gable, formed by the edges *e e* of two adjacent surfaces of the top C, the upper edges *e d* uniting and forming a hip, *f*, extending from the point *e* to the apex *d*, the design thus produced being unique and ornamental.

What I claim as my invention, and desire to secure by Letters Patent, is—

The design for the casing of a soda-water apparatus, herein shown and described.

Witness my hand this 18th day of November, A. D. 1873.

GEO. F. MEACHAM.

In presence of—

P. E. TESCHEMACHER,
JAS. F. ELLIS.
